UNITED STATES PATENT OFFICE.

MATHIAS S. EXE, OF HAYFIELD, MINNESOTA.

MAIL-BOX.

SPECIFICATION forming part of Letters Patent No. 742,850, dated November 3, 1903.

Application filed July 31, 1903. Serial No. 167,790. (No model.)

To all whom it may concern:

Be it known that I, MATHIAS S. EXE, a citizen of the United States, residing at Hayfield, in the county of Dodge and State of Minnesota, have invented a new and useful Mail-Box, of which the following is a specification.

This invention relates to mail-boxes of that class which are specially adapted to be used on rural-delivery routes; and it has for its object to provide a device of this class which shall possess superior advantages in point of simplicity, durability, ease of operation, and general efficiency.

15 A special object of my invention is to furnish a box of an approximately cylindrical shape with a lid normally disposed at the bottom thereof and which is mounted eccentrically and which shall be provided with 20 means whereby when the box is partially rotated upon its axis the lid shall be automatically opened, thus affording access to the interior, the lid being, furthermore, automatically held in an open position while 25 the contents of the box are being removed.

A further object of my invention is to provide a signal which may be readily lifted to an exposed position so as to indicate that mail-matter has been placed in the box, but 30 which in the act of opening the box is thrown back to an inoperative position, so that no time need be lost by the collector in stopping to examine the box, as is oftentimes the case when the parties removing the mail-matter 35 from the box forget to throw the signal back to inoperative position.

With these and other ends in view my invention consists in the improved construction, arrangement, and combination of parts 40 which will be hereinafter fully described and particularly pointed out in the claims.

In the accompanying drawings, Figure 1 is a sectional end elevation showing the box open. Fig. 2 is a sectional end elevation 45 showing the box closed. Fig. 3 is a detail view showing the inside of the cover of my improved mail-box.

Corresponding parts in the several figures are indicated by similar numerals of reference.

The body of my improved mail-box is of approximately cylindrical shape, having a

longitudinal opening 2, from which flaring flanges 3 extend downwardly, said flaring flanges being reinforced by or connected with 55 riveted flanges 4. The ends 5 of the box are provided with reinforcing-washers 6, which are disposed eccentrically, as shown, and from which extend the pivots or axes 7, by means of which the box is pivotally connected with brackets 8, extending from a post or other suitable support 9.

The cover 10 of the box, which is hingedly connected at 11 with the body of the same, is provided at the ends thereof with segmental 65 flanges 12. Securely connected with the axes 7 are short brackets 13, and longer links 14 pivotally connect the flanges 12 of the cover with the free ends of the brackets 13. The cylindrical body of the box is provided with 7c a suitable handle 16. The position of the respective parts when the box is closed will be seen in Fig. 2 of the drawings, by reference to which it will appear that the brackets 13 and links 14 are practically folded 75 together within the box. When the handle 16 is pulled in the direction of the arrow shown in Fig. 2, the entire box is turned upon its eccentric axis, and the toggle-link 14, under the stress of the arm 13, which is 80 securely connected with the axis, will gradually push upon the cover until it assumes the position shown in Fig. 1 of the drawings, by reference to which it will be seen that said cover is braced or retained in an 85 open position while the contents of the box are being removed or while matter is placed therein. To close the box, the operation is simply reversed, as will be readily understood.

17 designates a target-plate, which is carried by a shank 18, having at its lower end a hook-shaped projection 19, at the heel end of which the said signal is pivotally connected with one of the brackets 8 by means of a 95 pin or bolt 20.

21 designates a pin attached to the adjacent end of the box and which by engaging the shank 18 holds the signal in an upright position when the box is closed.

22 is a pin which when the box is open and the pin 21 recedes from the shank 18 over the upper surface of the hook 19 engages the under side of said hook 19, thus throwing the

90

100

signal back into an inoperative or unexposed position.

In Fig. 3 of the drawings I have illustrated a detail view showing the inner side of the cover of the box, by reference to which it will be seen that said cover is provided with a separate receptacle 25, in which letters may be placed, while the body of the box is reserved for newspapers, packages, or weightier mail-matter. In the operation of this device it will be seen that when the box is thrown open the flaring flanges surrounding the lid or cover will when the box is opened form a stop, the rear portion of the said flaring flange abutting against and coöperating with the lid, and thereby preventing the box from being opened beyond a certain limit, which may be determined by the extent of the "flare" given to the rear portion of the flange 3. Said flange will also be found to be of considerable importance, in that it forms when the box is closed an absolute safeguard against the admission of snow or moisture into the box. The latter, it will be observed, may be readily turned upon its axis without danger of spilling the contents of the receptacle 25 into the body of the box, so that when the latter is opened the letters will occupy a conspicuous position in the said receptacle, which when the box is opened will be fully exposed to the view of the operator.

Having thus described my invention, I claim—

1. In a device of the class described, the combination of an approximately cylindrical casing, a hinged lid for the same, eccentrically-disposed pivotal supporting means for said casing, brackets extending from the pivotal supporting means, and links connecting said brackets with the lid.

2. In a device of the class described, a box constituting the body of the device, a lid hingedly connected with said box, said lid, when the box is closed, constituting the bottom thereof, eccentrically-disposed pivotal supporting means for the box, brackets extending from the pivotal supports, and links connecting the said brackets with the lid of the box.

3. In a device of the class described, an approximately cylindrical box having a hinged lid provided with flaring flanges, a handle suitably connected with said box, eccentrically-disposed pivotal supporting means, and flexible connections between said supporting means and the cover of the box.

4. In a device of the class described, a box or casing having eccentrically-disposed pivots, supports for the latter, a signal having a laterally-extending hook and having pivotal supporting means extending through the heel of said hook and engaging one of the

supports of the casing, a supporting pin adapted to engage the upper side of said hook, and an auxiliary pin adapted to engage the under side of said hook to thereby tilt the latter upon its supporting-pivot.

5. An eccentrically-mounted, pivoted box capable of turning upon its eccentric axis, a hinged lid for said box, and a link connecting said lid with a relatively fixed point.

6. A box pivotally mounted upon an axis eccentric to said box, a lid hingedly connected with said box and having flanges disposed interiorly of the box, and links connecting said flanges with relatively fixed points.

7. An eccentrically-mounted box having an opening, flaring flanges surrounding the said opening, a hinged lid for said opening, and a link connecting said lid with a relatively fixed point whereby said lid, when the box is rotated upon its eccentric axis, shall be thrown open and into contact with a portion of the flaring flange.

8. A pivoted, eccentrically-mounted box having an opening and a lid for said opening forming, when the box is closed, the bottom thereof, in combination with means connecting said lid with a relatively fixed point, whereby, when the box is rotated to bring its opening uppermost, the lid shall be swung open.

9. A mail-box having an opening and a lid for said opening normally constituting the bottom of the box, pivotal supporting means for said box, and means whereby the rotation of the box upon its axis will open the lid.

10. A mail-box having an opening, and a hinged lid for the same normally constituting the bottom of the box, link connection between said lid and a relatively fixed point whereby, by the rotation of the box, the lid shall be actuated, and stop means for supporting the box in its open position.

11. In a mail-box, a pivotally-supported box having an opening with a hinged lid, normally constituting the bottom of the box, and means for automatically opening said lid when the box is rotated upon its axis to bring said lid uppermost, and stop means to limit the movement of the box in the direction of opening the same.

12. A pivotally-mounted mail-box having an opening and a hinged lid normally constituting the bottom of the box, and an auxiliary receptacle mounted upon the inner side of said lid.

In testimony that I claim the foregoing as my own I have hereto affixed my signature in the presence of two witnesses.

MATHIAS S. EXE.
